UNITED STATES PATENT OFFICE.

RICHARD W. UHLIG, OF RUTHERFORD, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE.

1,114,316.

Specification of Letters Patent. Patented Oct. 13, 1914.

Application filed September 18, 1909. Serial No. 518,428.

To all whom it may concern:

Be it known that I, RICHARD W. UHLIG, a citizen of the United States, residing in Rutherford, in the county of Bergen and State of New Jersey, have invented certain new and useful Improvements in Type-Writing Machines, of which the following is a specification.

This invention is an improvement in line-spacing mechanisms for typewriters. The usual pawl and ratchet line-spacing mechanism for typewriting machines enables the operator to space his lines apart a set or fixed minimum distance or multiples of that distance—that is, to the usual regular extent. It frequently happens however that the operator desires to effect a fine alteration in the spacing of the typewritten lines in which event he must space the sheet by hand, depending upon his eye alone.

The principal object of my invention is to render it convenient in a machine having any line-spacing mechanism, for the operator to obtain minute regulation—that is, regulation complete, within extremes of adjustment—of the line-spacing when desired, as in feeding ruled sheets through the machine; whereby he is enabled either to space the typewritten lines at the intervals usual in typewriting machines, or to obtain variations and fine regulation of such intervals. To this end I have combined, with the main spacing mechanism such as a pawl-and-ratchet mechanism of the ordinary type, an auxiliary line-spacing mechanism, each mechanism being provided with an adjustment which in one case enables the operator to vary the line-spacing by unitary amounts or intervals in the usual manner, and in the other case, enables the operator to maintain any desired interval between the lines.

I provide, in addition to the usual unitary predetermined regular line-spacing mechanism, an auxiliary spacing mechanism including a supplementary clutch wheel for effecting fine variations in the line-space interval, and a dog to rotate the clutch wheel, and adjustment being provided to control the throw of the dog. Either of the line-spacing devices may be operated at will, by means of a single line-spacing lever of the usual type. A tooth operated by said lever is shiftably mounted so as to operate either the usual ratchet wheel or the clutch-dog, at will.

To shift the tooth to position to operate the clutching mechanism, I provide a switch actuated by a lever, which also releases or withdraws the usual spring-pressed detent from said ratchet wheel.

In the accompanying drawings, Figure 1 is a perspective view illustrating one embodiment of my invention applied to the Underwood type of front strike writing machines, and showing the parts in position to actuate the regular or main line-spacing mechanism. Fig. 2 is a similar view, showing the tooth in operative engagement with the irregular or auxiliary line-spacing mechanism. Fig. 3 is a perspective view like Fig. 2, with the clutch member removed. Fig. 4 is a side view, showing the tooth at rest in position to operate the auxiliary line-spacing mechanism, the positions assumed by the clutching dog and transmission lever when at rest also being shown. Fig. 5 is a top plan view of the parts in the positions shown in Fig. 4. Fig. 6 is a fragmentary top plan view, showing the tooth in position to engage the regular line-spacing mechanism. Fig. 7 is a detail perspective view of the switch, its lever and the detent-releasing arm. Figs. 8, 9 and 10 are detail rear side views showing, respectively, the inactive positions of the clutching dog and transmission lever on the carrier, the positions assumed when the tooth first engages the transmission lever, and the positions assumed by the carrier, clutching dog and transmission lever while the variable line-spacing mechanism is being operated. Fig. 11 is a perspective view showing the conformation of the transmission lever and the clutching dog. Figs. 12, 13 and 14 are diagrammatic views illustrating the positions assumed by the pawl when at rest, when first engaging the ratchet, and when at the end of its line-spacing stroke respectively. Fig. 15 is a detail view of the stop for the clutch and its adjusting mechanism. Figs. 16 and 17 are views illustrating respectively the position occupied by the pawl when about to operate the clutch mechanism, and the position of the pawl when operating such mechanism. Fig. 18 is a detail view of the detent and its releasing mechanism. A indicates a platen having an axle 1, journaled in the ends of a platen frame 2, of the Underwood style of front strike writing machine.

A line-spacing ratchet wheel 3, fast on the axle 1, is engaged by the usual spring-actuated detent 4, and as usual has invariable line-spacing teeth.

5 A slide 5 is mounted in the end of the platen frame, and is driven by the line-spacing lever 6, against the tension of a returning-spring 7. A pawl device or driver 8, having a spring 8^a, is pivoted to the slide 5 and is provided with a tooth 10 for rotating the ratchet wheel and platen. The pawl device 8 may carry a rearwardly extending beak 9 adapted to engage an adjustable shoulder 12 controlled by a regulating lever 13 constituting a line-space adjusting mechanism. The throw of the regulating lever 13 is controlled by an adjusting plate 36, one end of which is connected to the lever, the opposite end being slotted to receive a guiding stud 37, mounted on the platen frame. The adjusting plate is capable only of a limited number of adjustments, having for this purpose a series of apertures 38 releasably engaged by a spring 25 detent 39 to hold the regulating lever in adjusted position. The beak may be held elevated by the shoulder 12, as in Fig. 12, and therefore, holds the tooth 10 up in idle position through more or less of the line-spacing 30 stroke, whereby the ratchet and platen may be turned one, two or three regular or invariable steps as usual—that is, it may be turned through intervals of a fixed minimum (the distance between two successive teeth) 35 or multiples of said minimum.

The minutely variable line-spacing mechanism comprises an annular flange or ring 14 rotating with the platen and conveniently carried by the ratchet wheel 3, this flange 40 constituting a clutch element of a frictional line-spacing mechanism. A co-operating clutch member comprises a carrier 15 rotatable around the axle 1 and having a clutching dog 16 mounted to vibrate on the carrier, as by means of a pivot pin 16^a in alignment with the flange 14, the dog having a pair of jaws 17 to bite upon the flange 14. An interponent or transmission lever 20 is 45 pivotally mounted upon the carrier in such manner as to engage the outer end of the dog to cause it to bite firmly upon the annular flange.

When at rest, as shown in Fig. 8, the transmission lever abuts a check stop 21 on the carrier 15, the jaws of the clutching dog being released from the flange 14, and the dog itself abutting a return stop 22 rotatable about the axle 1, the position of the stop being conveniently adjustable by a screw 23 engaging a head 24 connected by a link 25 to the return stop 22. The dog is held against the return stop by a return spring 26 connected to and acting through the carrier 15. A permanent stop 27 arrests 60 the clutching dog to terminate the line-

space stroke, and the throw of the clutching dog and hence, of the platen, is determined by the distance between the fixed and adjustable stops.

Either the regular or the minutely variable line-spacing mechanism may be operated by the lever 6, and as one means to effect this result, I preferably form the pawl device of two members comprising the body portion 8 and the tooth 10, which latter is 70 adjustably secured to the body portion for lateral shifting movement. When the finely variable clutching line-spacing mechanism is to be operated, the pawl is shifted out of operative relation with the ratchet wheel 3 by a switch 28, operated by a handle 29 pivoted on the axle.

The free end of the switch is beveled at 28^a so that when the lever 29 is thrown forwardly, such beveled edge or cam will engage the free end of the tooth 10 to shift or force the same laterally out of operative position with the ratchet and against the tension of a spring 11.

With the shifting of the tooth 10 out of operative relation with the ratchet, the line-spacing clutch mechanism becomes operative. Conveniently, when the tooth is shifted out of operative position relative to the ratchet, it is shifted into operative relation 95 with the line-spacing clutch mechanism, as shown in Figs. 8 and 16, to actuate the clutching dog and platen. The line-spacing lever 6 can then be operated to drive the slide and pawl device rearwardly, the free end of the tooth 10 engaging the transmission lever 20, to cause the same to rock the clutching dog to bite on the flange 14, as shown in Fig. 9. Continued travel of the tooth 10 will throw the carrier, transmission lever and clutching dog into the position shown in Figs. 10 and 17 to rotate the flange and platen until the clutching dog contacts with the permanent stop 27. The tooth 10 rides along the edge of the switch 110 28 during the spacing operation, as shown in Fig. 17.

Upon the release of the lever 6, the slide 5 and pawl device are returned by spring 7 to their positions of rest, to allow the spring 26 115 to return the carrier 15, clutching dog 16 and lever 20 to their normal inactive positions.

It will be understood that during the ordinary line-spacing operation, the pawl 8 and tooth 10 do not travel straight backward, but dip down until the tooth engages the ratchet wheel 3, and then take a curvilinear course controlled by the movement of the ratchet wheel itself, as seen in Figs. 13 and 12. This sinuous movement of the pawl is not desired when the latter is driving the clutching dog; and hence I provide a means which will guide said pawl directly backward in a substantially horizontal direction. 13

This means consists of the switch 28 itself, upon the top of which rides a projection 34 provided on the pawl 8, as in Fig. 17.

The switch-controlling handle conveniently carries an arm 30 having a hook or dwell 31 to engage a stud 32 on the spring-actuated detent 4, to release the platen from the control of the detent when the switch has shifted the tooth out of operative relation with the ratchet, as shown in Fig. 16.

A forwardly projecting finger 35 on the slide 5 may, if desired, engage the rear face of the clutching dog, on the return of the slide to normal position, to aid in rocking the dog to disengage its jaws 17 from the flange 14, although this finger 35 may be omitted in some cases.

The switch 28 may conveniently have an additional function, namely, to lock the platen A against overthrow when it is line-spaced in the usual manner, by means of the ratchet 3 and pawl device. Said switch is beveled on its front under surface to overhang the tooth 10 of the pawl and arrest the same, its shape being such that the pawl cannot rise when it is in engagement with said overhanging part, as in Fig. 18.

It will be seen that my invention provides for the application of both kinds of line-spacing mechanism to the same machine.

Variations may be resorted to within the scope of the invention, and portions of the improvements may be used without others.

Having thus described my invention, I claim:

1. In a typewriting machine, the combination with a platen, of means for line-spacing by intervals of a fixed minimum and multiples of said minimum, line-spacing means, minutely adjustable, a device shiftable into the train of either of said line-spacing means, means whereby said device may be shifted, and a lever adapted to move said device for effecting the actuation by said device of either of the means aforesaid.

2. In a typewriting machine, in combination, a platen, means for effecting line spacing by intervals of usual regular extent, including a shiftable device, means operable by said shiftable device for line spacing said platen by intervals variable by irregular extents, an actuating lever, and means to shift said shiftable device.

3. In a typewriting machine, the combination with a platen, of ratchet feeding and frictional feeding line spacing devices for line-spacing by unitarily or minutely variable line-spacing intervals, and a lever-operated line-spacing actuator adapted to operate either line-spacing mechanism.

4. In a line spacing mechanism, a platen, a line-spacing wheel on said platen, a pawl for said wheel, a clutch-member carried by said wheel, a second clutch-member adapted to cooperate with said first-mentioned

clutch-member, and means for moving said pawl into position to engage said last-mentioned clutch-member.

5. In a typewriting machine, the combination with a platen, of means for line-spacing said platen by intervals of usual regular extent, a minutely variable line-spacing means, a lever-operated actuator for effecting the operation of one or the other of the line-spacing means, a switch whereby the actuator may be made to operate either of the respective line-spacing means, and devices for adjusting the extent of all the line-spacing strokes effected by said actuator.

6. In a typewriting machine, the combination with a platen, of a frictional line-spacing device, a ratchet line spacing device, including a shiftable actuator, and a switch for shifting the actuator from engagement with one to engagement with the other of the line-spacing devices.

7. In a typewriting machine, the combination with a platen, of unitarily and minutely variable line-spacing devices, including a shiftable actuator, a switch for throwing the actuator from position to operate one of the line-spacing devices to position to operate the other, a detent for one of the line-spacing devices, and a detent-release controlled by the movement of the switch.

8. In a typewriting machine, the combination with a platen, of a line-spacing mechanism including a ratchet and a clutch element connected with the platen, a co-operating clutch member to engage and operate the clutch element, and a shiftable actuator for operating the ratchet or the clutch member, respectively.

9. In a typewriting machine, the combination with a platen, of line-spacing mechanisms including a ratchet and clutch element, a co-operating clutch member, a shiftable actuator for operating the ratchet or the clutch-member respectively, a detent for the ratchet, a controlling lever having a switch and a detent release, to shift the actuator into position to operate the clutch member, and to simultaneously disengage the detent from the ratchet.

10. In a typewriting machine, the combination with a platen, of a line-spacing mechanism, including a ratchet wheel, and a minutely variable line-spacing device including a clutch element, the wheel and clutch element connected with the platen, a swinging clutching dog having jaws to bite upon the clutch element, a shiftable lever-actuated tooth adapted to actuate the ratchet wheel or the clutching dog respectively, and means for shifting the tooth to effect the operation of the wheel or the clutch element.

11. In a typewriting machine, the combination with a platen, of a line-spacing mechanism, including a ratchet connected with the platen, a detent for the ratchet, and

1. In a typewriting machine, the combination with a platen, of a line-spacing mechanism including a clutch element connected with the platen, a clutching dog having jaws to bite upon and rotate the clutch element, a lever having an arm to engage the detent, and a switch to shift the ratchet-operating member into position to operate said clutching dog and for releasing the detent from the ratchet simultaneously with the said shifting of the ratchet-operating member by the switch.
2. In a typewriting machine, the combination with a platen, of a line-spacing mechanism, including a ratchet and a clutch element connected with the platen, a coöperating clutch member capable of independent rotation relatively to the platen, a shiftable lever-actuated member to engage the ratchet or the clutch member to effect either unitarily or minutely variable line-spacing, and a switch for shifting the shiftable member.
3. In a typewriting machine, the combination with a platen, of a ratchet and a clutch element connected with the platen, a coöperating clutch element, a shiftable member for actuating the ratchet or the said coöperating element, a spring yieldingly retaining the coöperating clutch element in released position, and a switch for shifting the shiftable member into position to operate said coöperating clutch element.
4. In a typewriting machine, the combination with a platen, of a line-spacing mechanism including a clutch element connected with the platen, a clutching dog having a normally disengaged jaw to bite upon the clutch element, a lever-operated actuator for causing the engagement of the clutching dog and clutch element, to rotate the latter together with the platen, a pivotally supported lever interposed between the actuator and dog and engaged by the actuator, a liberating finger operated conjointly with the actuator; the clutching dog and interposed lever lying between the actuator and the liberating finger, and a returning spring for causing the finger to engage the clutching dog to aid in disengaging the latter and clutch element subsequently to the advance of the platen.
5. In a typewriting machine, the combination with a platen, of a line-spacing mechanism including a clutch element connected with the platen, a clutching dog having a normally disengaged jaw to bite upon the clutch element, an actuator for causing the engagement of the clutching dog and clutch element, to rotate the latter together with the platen, a pivotally-supported lever interposed between the actuator and dog and engaged by the actuator, a spring for returning the clutching dog and interposed lever to inactive position, and a stop to arrest the interposed lever.
6. In a typewriting machine, the combination with a platen, of a line-spacing mechanism including a clutch element connected with the platen, a clutching dog having a normally disengaged jaw to bite upon the clutch element, an actuator for the clutching dog, a lever between the actuator and dog, and a stop against which the clutching dog is normally held.
7. In a typewriting machine, the combination with a platen, of a line-spacing mechanism including an element whose movement is completely variable within extremes and an element whose movement is variable by units of a fixed minimum and multiples thereof, a detent for the last-mentioned element, an actuator for effecting the advance of the platen through one or the other of said elements, a switch for shifting the actuator, and means for disengaging the detent when the actuator is thrown into position to operate the minutely variable line-spacing element.
8. In a typewriting machine, the combination with a platen, of a finely variable line-spacing device for the platen, a line-spacing device whose throw is variable by predefined units, a shiftable actuator for effecting the advance of the platen through either of the line-spacing devices, a spring for maintaining the actuator in operative position relatively to the last named line-spacing device, and means for shifting the actuator to operative position relatively to the other line-spacing device.
9. In a typewriting machine, the combination with a platen, of a line-spacing mechanism including a ratchet connected to the platen, a shiftable lever-operated tooth for driving the ratchet, and a combined switch and stop for shifting the tooth out of operative relation with the ratchet when in one position and for arresting the tooth at the termination of its line-spacing stroke when in its opposite position.
10. In a typewriting machine, the combination with a platen, of a ratchet connected with the platen, a lever-operated slide, a pawl device mounted thereon, a line-space regulator controlling the operation of the pawl, a pawl shiftably mounted on said pawl device, a spring yieldingly holding the pawl in position to engage the ratchet, a clutch device also adapted to rotate the platen, and a switch adapted to shift the pawl out of operative engagement with the ratchet, against the tension of the spring, and into operative engagement with the clutch device.
11. In a typewriting machine, the combination with a platen, of a ratchet connected thereto, a lever-operated slide, a pawl device on said slide, a pawl adapted to engage the ratchet shiftably mounted on said pawl device, a minutely variable line-spacing de-

- vice, and a switch whereby the said pawl may be shifted from engaging relation to the ratchet to engaging relation with the minutely variable line-spacing device.
- 5 22. In a typewriting machine, the combination with a platen, of a finely variable line-spacing device, a line-spacing device whose throw is variable by intervals of a fixed minimum and multiples thereof, a lever-operated slide, a member pivoted on the slide, a pawl shiftably mounted on the pivoted member, a spring maintaining the pawl in operative relation with the last mentioned of said line-spacing devices, and a switch 10 for shifting the pawl against the tension of its spring into position for operating the other of said line-spacing devices.
23. In a typewriting machine, the combination with a platen and a usual line-spacing device connected thereto, of a minutely variable line-spacing device also connected to the platen, a shiftable pawl normally in position to engage said usual line-spacing device, means for shifting said pawl from 15 its normal position into a position where it is adapted to engage the minutely variable line-spacing device, and a lever adapted to move the said pawl when in either position, to turn the platen.
- 30 24. In a typewriting machine, the combination with a platen and a usual line-spacing device connected thereto, of a minutely variable line-spacing device also connected to the platen, a pawl for engaging either of 25 said line-spacing devices, means whereby said pawl may be placed into position to engage either of said line-spacing devices, and a means for moving the pawl when in either position, to turn the platen.
- 40 25. In a typewriting machine, the combination with a platen and a usual line-spacing device connected thereto, of a minutely variable line-spacing device also connected to the platen, a means adapted to be made 35 to engage either line-spacing device, and a lever for actuating said means.
26. In a typewriting machine, the combination with a platen, a line-spacing device therefor including a device whose throw is 45 variable by intervals of a fixed minimum and multiples thereof, and a regulator for the unitarily variable line-spacing device, of a finely variable line-spacing device connected with the platen, and a regulator for 50 the finely variable line-spacing device; a single operating lever being common to both of said line-spacing devices.
- 55 27. In a typewriting machine, the combination with a platen, a line-spacing mechanism therefor including a device whose throw is variable by intervals of a fixed minimum and multiples thereof, and a regulator for said line-spacing mechanism, of a minutely variable line-spacing mechanism, 60 a regulator for the latter, and a lever for 55 operating either line-spacing mechanism at will.
28. In a typewriting machine, the combination with a platen, a line-spacing mechanism therefor including a device whose throw is variable by intervals of a fixed minimum and multiples thereof, and a regulator for said line-spacing mechanism, of a minutely variable line-spacing mechanism, a regulator for the latter, a lever, and means for enabling the lever to operate either line-spacing mechanism at will.
29. In a typewriting machine, the combination with a platen, a line-spacing mechanism connected therewith including a device whose throw is variable by intervals of a fixed minimum and multiples thereof, and a lever-operated actuator, of a normally silenced finely variable line-spacing mechanism also connected with the platen, and a switch for throwing the actuator out of operative relation with the unitarily variable line-spacing mechanism and rendering the other effective.
30. In a typewriting machine, the combination with a platen, of a line-spacing mechanism including a device whose throw is variable by intervals of a fixed minimum and multiples thereof, a minutely variable line-spacing mechanism, both of said mechanisms connected with the platen, a line-spacing lever, a shiftable tooth driven by the lever, and means for throwing the tooth out of operative relation to the unitarily variable line-spacing mechanism and into 9 operation with the other.
31. In a typewriting machine, the combination with a platen, of a line-spacing device whose throw is variable by intervals of a fixed minimum and multiples thereof, a finely variable line-spacing device, a shiftable actuator for effecting the advance of the platen through the unitarily variable line-spacing device, means for shifting the actuator from position to coöperate with one 10 line-spacing device into position to coöperate with the other; the unitarily variable device including a ratchet and a detent; and means for disengaging the detent from the unitarily variable line-spacing device when 11 the actuator is thrown into position to operate the finely variable line-spacing device.
32. In a typewriting machine, the combination with a platen, of a line-spacing device whose throw is variable by intervals of a fixed minimum and multiples thereof, a finely variable line-spacing device, a lever, a shiftable tooth interposed between one of the line-spacing devices and the lever, a spring for maintaining the tooth in operative relation to its line-space device, and a switch for shifting the tooth out of operative position relatively to its line-spacing device when the remaining line-space device 120 is to be operated.

33. In a typewriting machine, the combination with a platen, of a ratchet connected with the platen, a lever-operated slide, a pawl device pivotally mounted thereon, a line-space regulator controlling the pawl device, said pawl device having its tooth pivotally mounted thereon, a spring engaging the tooth to yieldingly retain it in operative position relatively to the ratchet, a finely variable line-spacing mechanism normally silenced, and a switch for shifting the tooth out of operative position relatively to the ratchet, and rendering said finely variable mechanism effective.
34. In a typewriting machine, the combination with a platen, of a ratchet connected thereto, a spacing lever, a pawl device operated by the spacing lever having its tooth shiftably mounted thereon, to engage the ratchet, a switch for throwing the tooth out of position operatively to engage the ratchet, a rest on the pawl device for riding on the switch to retain the tooth out of engagement with the ratchet, and a finely variable line-space device adapted to be engaged by the tooth to be operated by the spacing lever.
35. In a typewriting machine, the combination with a platen, of a line-space mechanism having a toothed wheel for turning said platen to the extent of aliquot tooth spaces in said wheel, a variable element line-spacing said platen, an actuator for effecting the advance of the platen through one or the other of said line-spacing means, a switch for shifting the actuator, a detent for the toothed wheel, and means for disengaging the detent when the actuator is thrown into position to operate the minutely variable line-spacing means.
36. The combination with a platen and a manually operable reciprocating member, of a line-spacing device including a member whose throw is variable by units of usual regular extent, and a line-spacing device including a member whose throw is finely variable, each of such devices operable by said reciprocating member.
37. The combination with a platen and a manually operable member, of a line-spacing device including a member whose throw is variable by units of usual regular extent, a finely variable line-spacing device, and means for rendering either of said line-spacing devices operable by said manually operable member and the other of said line-spacing devices concomitantly inoperable by said manually operable member.
38. The combination with a platen and a manually operable lever, of a unitarily variable line-spacing device including a ratchet and a detent therefor, said ratchet connected to said platen, a normally silenced finely variable line-spacing device for said platen and means for rendering ineffective at will said unitarily variable line-spacing device including said detent, and simultaneous rendering said finely variable line-spacing device operable by said lever.
39. In a typewriting machine, the combination with a platen to be line-spaced, of a line-spacing device including a member whose throw is variable by predefined units, a finely variable line-spacing device, a shiftable means for rendering ineffective at will either of said line-spacing devices and concomitantly rendering the other of said line-spacing devices operative.
40. In a typewriting machine, the combination with a platen to be line-spaced, of a line-spacing device including a member whose throw is variable by predefined units, a finely variable line-spacing device, shiftable means for rendering ineffective at will either of said line-spacing devices and concomitantly rendering the other of said line-spacing devices operative, and means for holding said shiftable means in either position to which it may be shifted.
41. In a typewriting machine, the combination with a platen to be line-spaced, of a line-spacing device including a member whose throw is variable by predefined units, a finely variable line-spacing device, a reciprocating pawl or driver capable of operating either of said line-spacing devices, and means for shifting said reciprocating driver from one line-spacing device to the other at will.
42. In a typewriting machine, the combination with a platen to be line-spaced, of a line-spacing device including a member whose throw is variable by predefined units, a finely variable line-spacing device, a reciprocating pawl or driver capable of operating either of said line-spacing devices, a device for shifting said reciprocating driver from one line-spacing device to the other and holding it there, and means to return said driver.
43. The combination with a typewriting machine having a platen and ratchet, of a minutely variable line-spacing device, a pawl normally adapted to operate said ratchet and shiftable to operate said minutely variable line-spacing device, means for shifting said pawl, and means for actuating said pawl when in either normal or shifted position.

RICHARD W. UHLIG.
